F. C. MATTHEWS,
DISTRIBUTER FOR FEED SPOUTS,
APPLICATION FILED MAY 3, 1915.

1,173,451.

Patented Feb. 29, 1916.

UNITED STATES PATENT OFFICE.

FRED C. MATTHEWS, OF ORANGEVILLE, OHIO.

DISTRIBUTER FOR FEED-SPOUTS.

1,173,451.

Specification of Letters Patent. Patented Feb. 29, 1916.

Application filed May 3, 1915. Serial No. 25,573.

To all whom it may concern:

Be it known that I, FRED C. MATTHEWS, a citizen of the United States, residing at Orangeville, in the county of Trumbull and State of Ohio, have invented certain new and useful Improvements in Distributers for Feed-Spouts, of which the following is a specification, reference being had to the accompanying drawings:

10 My invention relates to distributing devices, and particularly to means for distributing material discharged from feed spouts, such as the spouts of elevators or in like circumstances.

15 The primary object of this invention is the provision of a device which is adapted to be detachably mounted upon the end of a feed spout and which will act to distribute and evenly mix material being discharged 20 through said spout.

25 A further object of the invention is to intimately intermingle coarse and fine particles being discharged from a spout so that the fine particles will not remain at the center of the pile formed by the discharged material while the coarse particles roll down to the margin of the pile, thus separating the different sizes of particles and depreciating the quality of the whole product. In other 30 words, my general object is to distribute material evenly over the surface of the bin into which the spout discharges, thereby preventing the separation of the coarse and fine particles from each other as occurs when no 35 device of this kind is used.

40 A further object of the invention is the provision of a distributing member provided with a distributing wheel having blades, this bladed distributing wheel being rotated either by the action of the material itself as it is discharged from the spout, or by any other suitable mechanical appliance.

45 A further object of the invention is to provide a device of this character which is attachable to and detachable from any ordinary elevator spout, and which is simple in construction, easy of operation, and may be readily repaired when desired.

50 Other objects will appear in the course of the following description.

My invention is illustrated in the accompanying drawing, wherein:

55 Figure 1 is a front elevation of my distributor applied to a spout; Fig. 2 is a side elevation of the same; Fig. 3 is a sectional view through the distributor; Fig. 4 is a sec-

tional view through the spout showing the clamp applied thereto.

Referring to the drawing, 2 designates a discharge spout such as the discharge spout 60 of an elevator, this spout discharging into a bin or other container. Detachably mounted upon the discharge spout is a supporting ring 3 which is preferably made of oppositely disposed sections and bolted together 65 by the bolts 4 and 5 so as to embrace and hold firmly upon the discharge spout. This clamping ring so formed of oppositely disposed sections is adapted to provide a transversely extending bar 6 from which depend 70 the rods 7. The rods 7 at their upper ends are adjustably engaged with the bar 6, and for this purpose the upper end of the rods 7 may be vertically slotted and bolts 8 be passed through the upwardly turned ends of 75 the bars 6 and through said slots, the bolts being engaged by nuts. By this means the rods may be not only adjusted vertically but may be adjusted angularly with relation to the spout 2. Disposed between the lower 80 ends of the rods 7 is a bottom cross bar 9 having upturned perforated ends through which bolts 10 pass, these bolts engaging the side rods 7. Preferably the upper bar 6 in actual practice is about twelve inches long, 85 while the lower bar 9 is about fourteen inches long.

Bolted or otherwise mounted upon the bar 9 which forms part of the supporting frame previously described, is a casting 11, 90 provided with a center bore 12, and extending upward from this bore is a sleeve 13. The lower end of this sleeve is formed with a bearing surface 14 adapted to coact with an antifriction ball 15. The upper end of 95 the sleeve is formed with an annular bearing 16 forming a ball race. Disposed within the sleeve 13 and rotatable therein, is a vertical shaft 17 which carries the distributing member proper. This distributing member consists preferably of an approximately conical body 18 having downwardly and outwardly diverging sides to the apex of which the shaft is connected in any suitable manner so that the distributing member may 105 rotate with the shaft. Mounted upon or formed on the outer face of this conical body 18 are a plurality of blades 19. Each blade extends helically with relation to the axis of the conical member, and the ends of the 110 blades project out beyond the conical member, as at 20, and are preferably slightly

curved upward. The inner edge of each blade is upwardly turned, as at 21. These blades may be attached to the conical member in any suitable manner, but as illustrated each blade is formed with a plurality of lugs 22 projecting at right angles to the blade and which are riveted or otherwise attached to the conical member. The body of each blade conforms closely to the face 10 of the conical member.

In the construction illustrated the force of the material descending through the spout 2 will act to rotate the distributing member by contact with the several blades, but I do not 15 wish to be limited to this as in some circumstances it will be desirable to positively rotate the distributing member, and in that case, as illustrated in dotted lines in Fig. 1, the shaft 17 is extended downward through 20 the bar 9 and is connected to any desired form of power transmission device, as for instance the belt or band 23.

While I do not wish to be limited to the use thereof, I may apply intermediate blades 25 24 between the blades 18 and disposed adjacent the lower end of the conical body. It will be noted that by adjusting the rods 7 and angularly adjusting the cross bar 9 the distributor may be centered beneath the discharge end of the spout so that the material discharged from the spout will have a uniform action upon the distributor.

The operation of my mechanism will be plainly obvious from what has gone before. 35 The material discharged from the spout will descend upon the distributing wheel or member, and the weight of the material will cause the wheel to revolve. The centrifugal force of the rapidly rotating wheel will 40 cause the material to spread over the bin and distribute the material evenly over the surface of the bin, thus entirely preventing the separation of the fine and coarse parts of the material from each other.

45 I have found in practice that a device of this kind is thoroughly effective in preventing the segregation of particles having dif-

ferent sizes, and evenly distributes the material, and is of particular value in elevators or like structures.

While I have described my device as applied to distribute material discharged from an elevator spout, it will of course be understood that it might be used in other situations, and it will likewise be understood that it may be modified in many respects without departing from the spirit of the invention.

Having thus described my invention, what I claim is:

1. A distributing device for elevator discharge pipes comprising a supporting frame including a clamp adapted to detachably engage a discharge pipe, and members depending from and adjustable with relation to the clamp, a cross bar carried by said members and adjustable with relation thereto, and a rotatable distributor mounted upon the cross bar.

2. A distributing device for elevator-discharge pipes comprising pipe engaging sections, oppositely disposed rods depending from said sections and angularly adjustable with relation thereto, a cross bar carried by said rods and angularly adjustable with relation thereto, and a distributing member carried by said cross bar and including a conical body having exterior helically arranged blades.

3. A distributing device for discharge pipes, comprising a supporting frame including a sectional clamp adapted to detachably engage the discharge pipe, side bars pivotally connected at one end to said clamp, a cross bar having an angularly adjustable connection with the other ends of the side bars, and a distributor rotatably mounted upon said cross bar.

In testimony whereof I hereunto affix my signature in the presence of two witnesses.

FRED C. MATTHEWS.

Witnesses:

WILLIAM A. MAITLAND,
WALLACE C. LEFFINGWELL.
